UNITED STATES PATENT OFFICE

EUGEN PRESTINARI, OF IRVINGTON, NEW JERSEY, ASSIGNOR TO GEMEX COMPANY, OF NEWARK, NEW JERSEY, A CORPORATION OF NEW JERSEY

CHAIN

Application filed April 15, 1930. Serial No. 444,454.

This invention relates to a band chain, more particularly adapted for bracelet use; and has for its object to provide a link chain construction having the appearance of small 5 alternating links which are compactly related with reference to their longitudinal relationship.

A further object of the invention is to provide a chain of sheet stock in which the arms 10 embrace a longitudinally-extending body portion and yet lie with their outer surfaces in substantially the same plane to present an even, smooth appearance to the top of the bracelet.

15 With these and other objects in view, the invention consists of certain novel features of construction, as will be more fully described, and particularly pointed out in the appended claims.

20 In the accompanying drawings:

Fig. 1 is a top plan view of the chain embodying this invention.

Fig. 2 is a bottom view of a portion of the chain.

25 Fig. 3 is a sectional view with the bottom portion of the chain removed.

Fig. 4 is a view similar to Fig. 3, showing a single link.

Fig. 5 is a perspective view of the blank 30 from which the link is formed.

Fig. 6 is a perspective view of a complementary link which is alternated therewith in the series.

35 Fig. 7 is a perspective view showing the link of Fig. 5 partially bent into finished position.

Fig. 8 is a perspective view of a link bent into finished position.

40 Fig. 9 is a longitudinal section thru the chain.

In constructing a chain of the type presenting alternating links, it is found desirable to cause the links to be compactly related with reference to the length of the chain 45 with the links which are staggered with relation to each other overlapping and being overlapped substantially equal amounts with reference to the links at either end thereof; and it is also found of advantage to provide a construction in which the top surface of the

chain will lie in substantially a single plane and present an even, smooth appearance; and in order to accomplish this result, I have so formed each of the links of the series as to cause a portion of the body of the link to extend in a longitudinal direction with reference to the chain with portions for receiving the arms being depressed a thickness substantially equal to the thickness of the arms, 55 in order that the arms extending about this body portion may lie flush with the arms of the link to which they are connected and present an even, smooth outer surface; and the following is a detailed description of the 60 present embodiment of the invention showing the preferred means by which these 65 advantageous results may be accomplished:—

With reference to the drawings, 10 designates one link and 11 the other link of the series which are alternated with one another throughout the length of the chain, the arms extending from the body being staggered as shown and interlocked one with another. Each of these links is provided with arms 12 70 extending from the body 13, which body is bent into substantially L-shape intermediate its edges, as illustrated in Fig. 7, with the longer leg 14 of the L extending longitudinally of the chain and the shorter leg 15 extending laterally or in a direction of the 75 thickness of the chain.

The arms 12 project beyond the longitudinally-extending portion 14 of the body which are depressed, thus severing this portion from the arms, the same being looped or folded about the longitudinally-extending portion 14 of the body of the next link and setting in the depressed portion, as apparent from Fig. 8, with their end portion 16 extending back toward the body and lying substantially 80 parallel with the portion 17 forming the upper surface of the chain.

Arms 18 also extend from the opposite edge of the body and project as at 19 (see Fig. 9) to meet the portion 16 causing the ends to abut and complete the bottom of the link to prevent accidental detachment. The links thus connected are hingedly related causing the 85 chain to be exceedingly flexible.

The top surface 20 of each of the arms 90

is unbroken, while the bottom surface is broken by the joint 21 of the abutting ends of the arms extending laterally of the chain. As each of the links extends about the longitudinally extending portion 14 of the body, they are held in close compact relationship with reference to the longitudinal extent of the chain and as the dimension of this portion of the body is substantially one-half of 10 the top surface 20 of the arm and body, each of the links will overlap the next link substantially the same distance thus forming a symmetrical construction which is highly desirable in an ornamental chain of this character.

The foregoing description is directed solely towards the construction illustrated, but I desire it to be understood that I reserve the privilege of resorting to all the mechanical 20 changes to which the device is susceptible, the invention being defined and limited only by the terms of the appended claims.

I claim:

1. In a chain, a series of sheet metal links, 25 each comprising a body extending transversely of the chain and L-shape in cross section, arms projecting beyond the edge of the longitudinally-extending portion of the body and embracing the body of the next link to 30 hingedly connect the links together.

2. In a chain, a series of sheet metal links, each comprising a body extending transversely of the chain and L-shape in cross section with the longer leg of the L extending 35 longitudinally of the chain, arms projecting beyond the edge of the longitudinally extending leg of the body and embracing the body of the next link to hingedly connect the links together.

40 3. In a chain, a series of sheet metal links, each comprising a body extending transversely of the chain with a sheet metal portion extending longitudinally thereof, arms projecting beyond the edge of the longitudinally-extending portion of the body and embracing the body of the next link to hingedly connect the links together, the portions of 45 the longitudinally extending portion of the body between the points of projection of the arms being depressed inwardly of the link substantially the thickness of the stock of the arms to receive the arms therein and permit them to lie flush with the outer surface of the chain.

55 4. In a chain, a series of sheet metal links, each comprising a body extending transversely of the chain and L-shape in cross section with the longer leg of the L extending longitudinally of the chain, arms projecting 60 beyond the edge of the longitudinally extending leg of the body and embracing the body of the next link to hingedly connect the links together, the portions of the longitudinally extending leg of the body between the points 65 of projection of the arms being depressed

inwardly of the link substantially the thickness of the stock of the arms to receive the arms therein and permit them to lie flush with the outer surface of the chain.

5. In a chain, a series of sheet metal links, 70 each comprising a body extending transversely of the chain and L-shape in cross section, arms projecting beyond the edge of the longitudinally-extending portion of the body and looped about the body of the next link 75 and extending substantially parallel with the said longitudinally extending portion of the body.

6. In a chain, a series of sheet metal links, each comprising a body extending transversely of the chain and L-shape in cross section, arms projecting beyond the edge of the longitudinally-extending portion of the body and looped about the body of the next link 80 and extending substantially parallel with the 25 said longitudinally extending portion of the body, and arms projecting from the opposite edge of the body to meet the looped arms.

7. In a chain, a series of sheet metal links, each comprising a body extending transversely of the chain and L-shape in cross section with the longer leg of the L extending longitudinally of the chain, arms projecting 90 beyond the edge of the longitudinally-extending leg of the body and embracing the body 95 of the next link and extending substantially parallel with the said longitudinally extending portion of the body to hingedly connect the links together.

8. In a chain, a series of sheet metal links, 100 each comprising a body extending transversely of the chain and L-shape in cross section with the longer leg of the L extending longitudinally of the chain, arms projecting beyond the edge of the longitudinally-extending leg of the body and looped about the 105 body of the next link and extending substantially parallel with the said longitudinally extending portion of the body to hingedly connect the links together, and arms projecting 110 from the opposite edge of the body to meet the looped arms.

In testimony whereof I affix my signature.

EUGEN PRESTINARI.
